UNITED STATES PATENT OFFICE.

FLORA BARNETT, OF NEW YORK, N. Y.

DESIGN FOR A HAT-RIM COVERING.

SPECIFICATION forming part of Design No. 25,428, dated April 21, 1896.

Application filed January 2, 1895. Serial No. 533,639. Term of patent 31 years.

To all whom it may concern:

Be it known that I, FLORA BARNETT, a citizen of the United States, residing in the city, county, and State of New York, have invented and produced a new and original Design for the Coverings of Hat-Rims, of which the following is a specification, reference being had to the accompanying drawing illustrating such design.

10 The rim-covering 4, of lace, netting, or the like, is radially fluted, corrugated, or plaited, as at 5, and has an opening 6 for the passage therethrough of the crown of the hat, which opening is on one side of the center of the rim.

The leading feature of the design rests in 15 a flat hat-rim covering having radial flutes or plaits and having the crown-opening arranged on one side of the center of the rim.

What I claim as new, and desire to secure by Letters Patent, is—

20 The design for a hat-rim covering substantially as shown and described.

Dated New York, December 29, 1894.

FLORA BARNETT.
